FOREIGN PATENT DOCUMENTS

EP 000314224 * 3/2005

Primary Examiner—Ian Simmons*Assistant Examiner*—Carissa C Fitts(74) *Attorney, Agent, or Firm*—Volpe and Koenig, P.C.(57) **CLAIM**

The ornamental design for a flow regulator, as shown and described.

DESCRIPTION

FIG. 1 is a top perspective view of a flow regulator showing my new design;

FIG. 2 is a front elevational view of the flow regulator of FIG. 1;

FIG. 3 is a top plan view of the flow regulator of FIG. 1;

FIG. 4 is a side elevational view of the flow regulator of FIG. 1;

FIG. 5 is a back elevational view of the flow regulator of FIG. 1; and,

FIG. 6 is a bottom plan view of the flow regulator of FIG. 1, wherein the dashed lines show environmental matter for illustrative purposes only and do not form part of the claimed design.
